ATTORNEYS.

UNITED STATES PATENT OFFICE.

WILLIAM S. ORR, OF MASSILLON, OHIO, ASSIGNOR TO THE CENTRAL STEEL COMPANY, OF MASSILLON, OHIO, A CORPORATION OF OHIO.

COVER-OPERATING MECHANISM.

Application filed October 14, 1924. Serial No. 743,574.

To all whom it may concern:

Be it known that I, WILLIAM S. ORR, a citizen of the United States, and a resident of Massillon, county of Stark, and State of Ohio, have invented a new and useful Improvement in Cover-Operating Mechanisms, of which the following is a specification, the principle of the invention being herein explained and the best mode in which I have contemplated applying that principle, so as to distinguish it from other inventions.

The present improvements, relating, as indicated, to cover operating mechanism, have more particular regard to the provision of improved means for removing and replacing, as desired, the covers on soaking pits and like furnaces in which an opening is provided in the top for the purpose of securing access to the furnace interior, whether this be to introduce and remove ingots, as in the case of a soaking pit, or fuel, in the case of furnaces of different type. Such covers ordinarily are quite heavy, consisting in the case of soaking pits of a steel casting with fire-brick lining inset.

One principal object of the present invention is to provide means whereby a cover of this type may be more readily manipulated and without unnecessary jar or shock, particularly when the cover is being replaced inasmuch as this is liable to damage the edge of the furnace opening. It will be understood that any cracks left about such opening will allow the escape of flame and highly heated gases with consequent damage to furnace and door. For the same reason it is necessary that the door always have a tight fit so as to securely close the opening.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a plan view showing the general arrangement of a pit furnace equipped with my improved cover operating mechanism certain portions of the upper carrying frame being broken away; Fig. 2 is a longitudinal section of the same, taken on the vertical

plane indicated by the line 2—2, Fig. 1; Fig. 3 is a vertical section of a detail taken on the plane indicated by the line 3—3, Fig. 1; and Fig. 4 is a transverse section of another detail taken on the plane indicated by the line 4—4, Fig. 1.

The pit furnace 1, as shown in Fig. 2 of the drawings, is of the usual design, as is also in the main the cover 2 that is provided to seal the opening 3 of said furnace. The latter, in other words, consists of a rectangular casting, the under side of which is hollow and faced with fire-brick 4 over the area corresponding with the opening 3 when the cover is in place.

On each side the casting that thus constitutes the cover is formed with a laterally projecting web 5 to which is attached a longitudinally disposed cradle 6. Such cradle is thus attached to web 5 through the medium of two bolts 7 that pass vertically through suitably spaced apertures in such web and registering apertures in the respective ends of the cradle. As shown in the detail view of Fig. 3, such aperture in the case of the web is surrounded by an upstanding boss 8 that enters a downwardly directed socket 9 in the end of the cradle so as to hold the parts in proper alignment. The bolt is allowed a certain amount of play in the apertures in the web and cradle ends, its lower end being held in place by means of a key 10, while a compression spring 11 is interposed between the corresponding end of the cradle and a cup-shaped washer 12 adjustably secured in place on the upper projecting end of the bolt by means of a nut 13.

Movably mounted, as will be presently described, so as to normally project over the furnace opening 3, as shown in Fig. 2, are two horizontally extending supporting arms 15 that are connected together by transverse and diagonal braces 16 so as to constitute a rigid frame structure. The outer ends of these arms are respectively connected with the corresponding cradles 6 by means of links 17 and 18, such last mentioned link including an integral upstanding arm 19 so as to constitute in effect thereof a double arm lever that is fulcrumed on the supporting arm 15 at its point of pivotal attachment thereto. A third link 20 is pivotally attached to one of the arms 15 and the inner end of the corresponding cradle, such link being substantially equal in length to the

adjacent link 18 and parallel therewith so that although the cover may be oscillated about the forward ends of said arm, it will nevertheless be maintained at all times with its under side in a substantially horizontal plane.

The supporting frame structure for the door, which the arms 15 with the braces 16 are thus seen to constitute, is oscillatorily mounted on a transverse shaft 21, the respective ends of which are journaled in wheeled carriages or trolleys 22. The latter are arranged to run on parallel rails 23 that present a horizontal contact surface except at 10 their ends adjacent the furnace opening 3 where they slope downwardly at an angle of approximately 45 degrees towards such opening. Because of the wear that will be imposed in use on such downwardly inclined 15 ends, a block 24 of specially hardened steel is inset at this point in each rail (see Fig. 2). The rear ends of the respective arms 15 are provided with rollers 25 that, as best shown 20 in Fig. 4, are guided on the under side of the same rails 23 on which the trolleys 22 run. The frame of the trolley 22 that is located 25 on the same side, i. e., in alignment with the upstanding arm 19 of link 18, is provided likewise with an upstanding arm 26 and this is connected by means of a link 27 30 with said arm 19.

The rails 23, it will be observed, are spaced sufficiently far apart to afford ample clearance therebetween for passage of the cover 2 as the arms 15 are moved from the position shown in full lines in Fig. 2 to the position shown in dotted outline and as will be noticed, the inclined portion of the rail provides a cam action to raise or lower the frame and cover. The first effect of such movement, due to the connection afforded by link 27 between arm 19 of link 18 and arm 26 on carriage or trolley 22, will be to lift the cover as a result of the oscillation about shaft 21 of this and the companion trolley as they move off the inclined portions 24 of the rails 23 onto the horizontal portions of such rails. Once the cover is thus lifted, it will be carried at a uniform height as the trolleys are retracted along the rails by continued movement of arms 15. The successive positions occupied by the link connection just referred to in thus initially lifting the cover are likewise shown in dotted outline on Fig. 2 and, as thereby made clear, the retraction of the forward ends of arms 15 is compensated for by the outward swinging movement imparted to link 18, the combined result being that the cover is lifted in a substantially vertical direction, being prevented from tilting about the lower ends of links 17 and 18 by means of link 20, as hereinbefore described.

Upon reverse movement of the parts, the cover will of course be lowered instead of

raised, but such lowering movement will likewise be in a substantially vertical direction after the cover has been brought into position over the opening 3. When it is finally brought into contact with the surrounding furnace wall, the compression springs 11 will allow for further movement, within reasonable limits, of the supporting or actuating parts, so that the cover may finally rest in effect under its own weight and evenly bear all around on the edge of the opening 3. 70 75

For the purpose of moving trolleys 22, and thus the arms 15, back and forth in the fashion just described, any suitable operating means may be employed. In the drawings, however, I show a crank drive which permits of positive limitation of the lowering movement of the cover and thus prevents any danger of slamming onto the furnace wall surrounding opening 3. This drive comprises a motor driven shaft 30, suitably mounted in a supporting framework to one side of the furnace, or, in other words, at the outer ends of rails 23. The electric motor 31 and interposed reduction gearing 32 will be of standard construction. The respective ends of crank shaft 30 carry parallel crank arms 33, the outer ends of which are pivotally connected by means of link 34 with shaft 21, on which arms 15 are mounted. It will accordingly be seen that oscillation of shaft 30 in a clockwise direction, as viewed in Fig. 2, will draw the trolleys 22 and thus the arms 15 to the right, while oscillation of the shaft 30 in the opposite direction will produce a reverse movement of the parts in question. It will be noted that when shaft 30 has been thus oscillated in a counter-clockwise direction to bring the cover to its closing position, the cranks 33 and links 34 are fully extended so that no further movement in this direction can by any possibility be imparted to the trolleys 22. Furthermore, the later stage of such movement is relatively slow due to the change in the angular position of the cranks and as a result slamming of the cover is substantially entirely avoided. Instead, it will be lowered gently and in such manner as to avoid damage to the wall of the furnace surrounding opening 3.

The total angle of oscillation of the cranks 33 will be slightly less than 180 degrees, as shown, and spring bumpers 35, one on each side, are provided to engage with the arms when they are brought to their other limiting position. 120

Other modes of applying the principle of my invention may be employed instead of the one explained, change being made as regards the mechanism herein disclosed, provided the means stated by any of the following claims or the equivalent of such stated means be employed. 130 125

I therefore particularly point out and distinctly claim as my invention:—

1. In mechanism of the character described, the combination with a horizontally disposed cover; of a horizontally movable frame extending over and suitably attached to said cover; means for carrying said frame horizontally, and inset cam-acting means in the path of said means for raising or lowering the frame. 5
2. In mechanism of the character described, the combination with a horizontally disposed cover; of a horizontally movable frame extending over and suitably attached to said cover; means for carrying said frame horizontally, a track for supporting said means, and wear-resistant inset cam portions along said track for raising or lowering the frame. 15
3. In mechanism of the character described, the combination with a horizontally disposed cover; of a horizontally movable frame extending over and suitably attached to said cover; means for carrying said frame horizontally, a track for supporting said means, and sloping wear-resistant inset portions at the end of the track adjacent the furnace for raising or lowering the said frame. 25
4. In mechanism of the character described, the combination with a horizontally disposed cover; of a track extending horizontally from the normal closed position of said cover, the end of the track adjacent such normal closed position of the cover inclining downwardly; supporting means movable along said track; a frame oscillatorily supported by said means; means connecting the inner end of said frame with said cover; and means between said cover and said supporting means for maintaining the cover horizontal upon movement of said supporting means. 35
5. In mechanism of the character described, the combination with a horizontally disposed cover; of a track extending horizontally from the normal closed position of said cover, the end of the track adjacent such normal closed position of the cover inclining downwardly; supporting means movable along said track; a frame oscillatorily supported by said means; link means connecting the inner end of said frame with said cover; and equalizing connections between said supporting means and link means whereby the cover is maintained horizontal upon movement of the supporting means. 50
6. In mechanism of the character described, the combination with a horizontally disposed cover; of parallel rails extending horizontally from the normal closed position of said cover, the inner ends of said rails inclining downwardly; trolleys movable along said rails respectively; a transverse shaft connecting said trolleys; a frame oscillatorily mounted on said shaft and comprising longitudinally extending arms, the outer ends of said arms being guided for movement parallel with said rails; links connecting the inner ends of said arms with said cover, one of said links being provided with an upwardly extending arm; an upstanding arm on the corresponding trolley; and another link connecting said two arms. 70
7. In mechanism of the character described, the combination with a horizontally disposed cover, of parallel rails extending horizontally from the normal closed position of said cover, the inner ends of said rails inclining downwardly; trolleys movable along said rails, respectively; a transverse shaft connecting said trolleys; a frame oscillatorily mounted on said shaft and comprising longitudinally extending arms, the outer ends of said arms being guided for movement parallel with said rails; two cradles resiliently attached to said cover adjacent the respective sides thereof; links connecting the inner ends of said arms with said cradles, respectively, one of said links being provided with an upwardly extending arm; an upstanding arm on the corresponding trolley; and another link connecting said two arms. 80
8. In mechanism of the character described, the combination with a horizontally disposed cover, of parallel rails extending horizontally from the normal closed position of said cover, the inner ends of said rails inclining downwardly; trolleys movable along said rails, respectively; a transverse shaft connecting said trolleys; a frame oscillatorily mounted on said shaft and comprising longitudinally extending arms, the outer ends of said arms being guided for movement parallel with said rails; two cradles resiliently attached to said cover adjacent the respective sides thereof; links connecting the inner ends of said arms with said cradles, respectively, one of said links being provided with an upwardly extending arm; an upstanding arm on the corresponding trolley; and another link connecting said two arms. 85
9. In mechanism of the character described, the combination with a horizontally disposed cover; of parallel rails extending horizontally from the normal closed position of said cover, the inner ends of said rails inclining downwardly; trolleys movable along said rails respectively; a transverse shaft connecting said trolleys; a frame oscillatorily mounted on said shaft and comprising longitudinally extending arms, the outer ends of said arms being guided for movement parallel with said rails; links connecting the inner ends of said arms with said cover, one of the aforesaid links additionally connecting the corresponding arm and cradle; an upstanding arm on the trolley corresponding to the link with upwardly extending arm; and another link connecting said two arms. 100
10. In mechanism of the character described, the combination with a horizontally disposed cover; of parallel rails extending horizontally from the normal closed position of said cover, the inner ends of said rails inclining downwardly; trolleys movable along said rails respectively; a transverse shaft connecting said trolleys; a frame oscillatorily mounted on said shaft and comprising longitudinally extending arms, the outer ends of said arms being guided for movement parallel with said rails; links connecting the inner ends of said arms with said cover, one of the aforesaid links additionally connecting the corresponding arm and cradle; an upstanding arm on the trolley corresponding to the link with upwardly extending arm; and another link connecting said two arms. 110
11. In mechanism of the character described, the combination with a horizontally disposed cover; of parallel rails extending horizontally from the normal closed position of said cover, the inner ends of said rails inclining downwardly; trolleys movable along said rails respectively; a transverse shaft connecting said trolleys; a frame oscillatorily mounted on said shaft and comprising longitudinally extending arms, the outer ends of said arms being guided for movement parallel with said rails; links connecting the inner ends of said arms with said cover, one of the aforesaid links additionally connecting the corresponding arm and cradle; an upstanding arm on the trolley corresponding to the link with upwardly extending arm; and another link connecting said two arms. 115
12. In mechanism of the character described, the combination with a horizontally disposed cover; of parallel rails extending horizontally from the normal closed position of said cover, the inner ends of said rails inclining downwardly; trolleys movable along said rails respectively; a transverse shaft connecting said trolleys; a frame oscillatorily mounted on said shaft and comprising longitudinally extending arms, the outer ends of said arms being guided for movement parallel with said rails; links connecting the inner ends of said arms with said cover, one of the aforesaid links additionally connecting the corresponding arm and cradle; an upstanding arm on the trolley corresponding to the link with upwardly extending arm; and another link connecting said two arms. 120
13. In mechanism of the character described, the combination with a horizontally disposed cover; of parallel rails extending horizontally from the normal closed position of said cover, the inner ends of said rails inclining downwardly; trolleys movable along said rails respectively; a transverse shaft connecting said trolleys; a frame oscillatorily mounted on said shaft and comprising longitudinally extending arms, the outer ends of said arms being guided for movement parallel with said rails; links connecting the inner ends of said arms with said cover, one of the aforesaid links additionally connecting the corresponding arm and cradle; an upstanding arm on the trolley corresponding to the link with upwardly extending arm; and another link connecting said two arms. 130

- 4
- 5 said cover, one of said links being provided with an upwardly extending arm; an up-
standing arm on the corresponding trolley; another link connecting said two arms; an
5 oscillatory shaft mounted transversely of said rails adjacent their outer ends; and connec-
tions between said shaft and frame adapted to reciprocate the latter upon oscillation
of said shaft.
- 10 10. In mechanism of the character de-
scribed, the combination with a horizontally
disposed cover; of parallel rails extending
horizontally from the normal closed position
of said cover, the inner ends of said
15 rails inclining downwardly; trolleys move-
able along said rails respectively; a trans-
verse shaft connecting said trolleys; a frame
oscillatory mounted on said shaft and com-
prising longitudinally extending arms, the
20 outer ends of said arms being guided for
movement parallel with said rails; links
connecting the inner ends of said arms with
said cover, one of said links being provided
with an upwardly extending arm; an up-
25 standing arm on the corresponding trolley;
another link connecting said two arms; an
oscillatory shaft mounted transversely of
said rails adjacent their outer ends; a crank
on said shaft; and a link connecting said
30 crank with the shaft connecting said trolleys.
11. In mechanism of the character de-
scribed, the combination of a horizontally
movable cover; a supporting frame for said
cover reciprocable towards and from the
35 normal closed position of the latter; means
adapted to oscillate said frame to raise and
lower said cover incidentally to reciproca-
tion of said frame; an oscillatory shaft
mounted transversely of the direction of
40 movement of said frame; and connections
between said shaft and frame adapted to
reciprocate the latter upon oscillation of
said shaft.
12. In mechanism of the character de-
scribed, the combination of a horizontally
45 movable cover; a supporting frame for said
cover reciprocable towards and from the
normal closed position of the latter; means
adapted to oscillate said frame to raise and
lower said cover incidentally to reciproca-
50 tion of said frame; an oscillatory shaft
mounted transversely of the direction of
movement of said frame; a crank on said
shaft; and a link connecting said crank
with said frame.
13. In mechanism of the character de-
scribed, the combination of a horizontally
movable cover; a frame reciprocable to-
wards and from the normal closed position
of said cover; cradle means resiliently sus-
pending said cover from said frame; and
equalizing links between said frame and
said cradle means for maintaining the cover
horizontal during movement.
14. In mechanism of the character de-
scribed, the combination of a horizontally
movable cover; a frame reciprocable to-
wards and from the normal closed position
of said cover; two cradles resiliently at-
tached to said cover adjacent the respective
70 sides thereof; and links connecting said
frame with said cradles.
15. In mechanism of the character de-
scribed, the combination of a horizontally
movable cover; a frame reciprocable to-
wards and from the normal closed position
75 of said cover, said frame comprising two
horizontally extending arms; two cradles re-
siliently attached to said cover adjacent the
respective sides thereof; links connecting
80 the inner ends of said frame arms with said
cradles, respectively; and another link par-
allel with one of the aforesaid links addition-
ally connecting one of said arms and the
corresponding cradle.

85 Signed by me, this 29th day of September,
1924.

WILLIAM S. ORR.
